Patented June 26, 1928.

UNITED STATES PATENT OFFICE.

IRVIN R. WATERMON, OF OVERLAND, MISSOURI, ASSIGNOR OF ONE-HALF TO CONRAD REINEMER, OF OVERLAND, MISSOURI.

SURVEYOR'S APRON.

Application filed September 2, 1927. Serial No. 217,095.

My invention consists in the novel construction and combination of parts herein-after particularly described and distinctly claimed.

5 The object of my invention is to provide a new article of manufacture which consists of a new and improved surveyor's apron, and which is to be worn by surveyors, and which apron when in use, will provide a 10 more convenient way or means of carrying the tools and other necessary articles that a person engaged in surveying work has to use.

Heretofore, a person engaged in this form 15 of work found it necessary to carry all of his tool such as a plumb-bob, marking tool, rule, location-tacks, and other such small articles as are common in this line of work, in his pockets in his clothes, and the latter soon 20 became worn out due to the weight and constant wear of the above named articles in the persons pockets.

A further object of my invention is to 25 provide a surveyor's apron which will accommodate all these articles, and which will also be very simple in construction, durable in wear, and which will be of a very low cost to manufacture.

30 In the drawing: Fig. 1 is a front elevation of my improved surveyor's apron, showing each of the component parts in position, and

Fig. 2 is a section of same, the section being taken on the line 2—2 of Fig. 1.

35 Referring to the drawing by numerals, the numeral 1 designates the apron which is made of leather or other suitable material upon which is secured a suitable pocket 2 which is adapted to receive a plumb-bob 3 when the latter is not in use, and which may 40 be carried around from place to place without the danger of same being lost.

The numeral 4 designates a reel or other suitable device containing a coil spring or 45 other means for rewinding a cord 5 that is attached to the said plumb-bob 3, after the said cord 5 has been pulled out therefrom in using the said plumb-bob 3. The main purpose of this reel is to take up the slack cord 50 which is attached to the plumb-bob when the line is not being used. At present, when a person is surveying in the woods, and it becomes necessary for him to use a plumb-bob,

the cord is unwound from a ball of cord, carried in the pants or coat pocket, and after 55 using the plumb-bob, the latter is placed in a pocket and the cord thrown around the user's neck, and while walking through the woods to the next location, the cord usually becomes tangled in the underbrush, and it 60 often has to be cut in order to untangle the cord so to enable the surveyor to continue on his way to the next location.

The numeral 6 designates a pocket which 65 is adapted to hold the surveyor's marking tool, which is a cold-chisel, and which is used in marking lines in corner stones, sidewalks and other places having a hard surface; the cold-chisel is designated by the numeral 7.

The numeral 8 designates another suitable 70 pocket adapted to hold a rule 9 when the latter is not in use.

The numeral 10 designates a large pocket, 75 or pouch, and is for the purpose of carrying the location-tacks, a tape-line, knife, pencil and other such small articles that are necessary in the art of surveying. In order to prevent the above named articles from dropping out of the said pocket 10 when the user 80 of the apron stoops over for any reason, an elastic band, or other suitable means, 11 have been employed to hold the top portion 85 of the pocket in a closed position, but when it is necessary for the surveyor to remove any of the articles from the said pocket, the elastic band will stretch and allow the article to be removed, and then the pocket will immediately close again.

The numeral 12 designates a common belt 90 having the usual buckle 13 attached thereto. A suitable hook 14 is slidably secured to the said belt 12 and is used for the purpose of holding what is known as location pins. These pins (not shown) are so constructed 95 as to have a loop at one of their ends while their opposite end is sharpened to a point, and these pins are usually hung around the waist of the surveyor by means of a cord or small rope, but with my improved apron, the said pins may be easily fastened to the said hook 14. The said hook 14 is so constructed 100 as to permit it to be slid, or pushed, backward or forward so that the said pins 105 may hang in any desired position so as not to interfere with the wearer of the apron

when the latter finds it necessary to stoop, or while he is engaged in other work.

The numeral 15 designates a suitable strap that is secured to the said belt 12; the former being used as a shoulder-strap, and its purpose is to prevent the apron from sagging under the weight of the articles being carried in the series of pockets in the apron. This shoulder-strap 15 is made adjustable so as to enable the user of the apron to adjust the strap to fit the shoulder properly.

The said belt 12 is threaded through a series of slots 16 that are formed in the upper portion of the apron, and said belt may be adjusted by sliding said belt through said slots. The said belt is used to strap the apron around user's waist.

While I have illustrated certain details which I deemed to be particularly effective, and have illustrated a construction which is very easy to be assembled, I do not wish to be limited to these details as it is obvious that many changes might be made therein without departing from the spirit or scope of my invention.

Having thus described my invention, what I claim as new and desire to secure by Letters-Patent is:—

1. A surveyor's apron designed to be attached to a body supporting belt and adapted to have a series of pockets secured thereon for the purpose of carrying the necessary tools and small articles that are used by those engaged in the trade, and a spring reel secured thereon having a winding cord attached to a plumb-bob, and a holder for the plumb-bob so mounted on the apron as to maintain the plumb-bob in a convenient and readily accessible position for use.

2. An apron designed to be attached to a body supporting belt, and a spring-reel secured thereon having a winding cord attached to a plumb-bob, and a holder for the plumb-bob so mounted on the apron as to maintain the plumb-bob in a convenient and readily accessible position for use.

In testimony whereof, I have signed my name to this specification.

IRVIN R. WATERMON.
